DOILY PACKAGE

William A. Roehm, Rockville Centre, N. Y., assignor to Royal Lace Paper Works, Inc., Brooklyn, N. Y., a corporation of New York

Application June 21, 1952, Serial No. 294,899

6 Claims. (Cl. 206—57)

1

This invention is directed to paper doilies and packages wherein they may be shipped and stored in the hands of the ultimate purchaser without soiling or damage while awaiting use.

It is the common practice to merchandise doilies in the form of stacks of a dozen or more, within wholly or partially transparent envelopes commonly made from cellophane, glassine, or the like. Such envelopes afford satisfactory protection to the doilies until the envelope is opened, but generally the opening of the envelope causes it to be torn, so that the doilies are no longer adequately protected. When placed in drawers with linens, dish towels, and other articles, they become separated from one another, torn, soiled, and otherwise unfit for further use. A large percentage of the doilies packaged in this conventional manner are damaged and spoiled before they are used.

The object of the present invention is to provide a package in which doilies may be satisfactorily merchandised to the ultimate consumer and in which package they are adapted to remain secured until individually removed therefrom for use. Such a package thus becomes a permanent container for the doilies until the last one thereof has been used, after which the container is discarded.

In practically carrying out the invention, I provide each doily with an attaching tab joined to the body of the doily at a line of weakness. The doilies are so stacked that the tabs of all of them register with and overlie one another and as such constitute attaching devices whereby the stack may be secured to a backing of cardboard or the like which becomes a permanent holder for the doilies. Over the forward face of this backing and over the doilies secured thereto is placed a transparent sheet, serving as a cover, adhered to the backing along zones completely surrounding the doilies so as to form a sealed container therefor. This container effectually protects the doilies against soiling or damage during shipment and storage until the container is opened.

The backing is so formed that, when it is desired to remove a doily from the package, a portion of the backing may be broken away and this broken away portion constitutes a finger piece, whereby the doilies may be uncovered to permit of ready access, leaving the transparent sheet in a condition to thereafter serve as a flap cover for the doilies.

The package, in the hands of the ultimate consumer, may be hung up on the inside of a closet

2

door or in any other suitable place and serves as a continuing support and container for the doilies until all of the latter are used. The doilies are adapted to be removed from the package by individually tearing them from their several tabs.

Features of the invention, other than those adverted to, will be apparent from the hereinafter detailed description and appended claims, when read in conjunction with the accompanying drawings.

The accompanying drawings illustrate one practical embodiment of the invention, but the construction therein shown is to be understood as illustrative, only, and not as defining the limits of the invention.

Fig. 1 is a face view of the container as it is initially prepared and before introduction of the doilies thereinto.

Fig. 2 is a like view showing stacks of doilies of three different sizes, introduced into the container and secured in place therein by stapling the tabs of all of them to the backing.

Fig. 3 shows the upper part of the transparent sheet, which has thus far been folded back, now folded over and adhesively secured to the rear of the backing to form the finished container with enclosed doilies.

Fig. 4 shows the manner of opening the container to uncover the doilies.

Fig. 5 shows the container fully opened to permit the doilies to be selectively individually removed.

Fig. 6 is a like view showing the transparent sheet flap lowered to cover the doilies and with certain doilies suspended on a hook associated with the staple which holds the remaining doilies in place on the backing.

Fig. 7 is a section on the line 1—7 of Fig. 6, showing spaces where some of the doilies have been removed.

Fig. 8 is a view showing a single doily and illustrates the attaching tab extending from and integral with the doily but connected therewith at the line of weakness.

In making the package of this invention, I start with a substantially flat rectangular cardboard somewhat larger than the doilies to be mounted thereon. Across one end portion of this cardboard, and in spaced parallel relation to that end, is a line of slits or perforations 2, forming a line of weakness between the body of the cardboard and a lower marginal strip 3, which, when detached, may serve as a finger piece.

Over the front face of the flat cardboard 4, which constitutes a backing, is laid a transpar-

ent sheet 4 of flexible material, which may be of vinyl or any other suitable plastic or cellophane or the like. The width of this sheet corresponds to the width of the cardboard backing 1 and the lateral edges, as well as the bottom edge of the sheet, are registered with the edges of the backing, but the sheet 4 is sufficiently long to extend somewhat above the upper edge of the backing as indicated in Fig. 1.

After being brought into the relation shown in Fig. 1, the sheet 4 is marginally adhesively secured to the backing 1 along the marginal zones indicated by the light stippling in this figure; that is to say, throughout the front surface of the finger piece 3 and up along the lateral edges of the backing to points 6 spaced from the upper edge of the backing. This latter spacing is provided so that, after the sheet 4 has been attached to the backing as described, the upper portion of this sheet may be folded back, as shown in Fig. 2, to permit a plurality of stacks of doilies D, D1, D2 to be introduced into the resulting container and secured to the backing 1 as shown.

To permit this attachment, each of the doilies is provided with one or more attaching tabs 7, one of which is shown in Fig. 8. This tab may be of any convenient size and shape and associated with the doilies in any desired manner. However, I prefer to utilize for this tab, a portion of the scrap which is normally cut away from the stock from which the doilies are made. In other words, all of the scrap is cut away and separated from the doily except a portion suitable to form the tab 7, that tab being left integral with and attached to the doily at a line of weakness 8, so that the doily proper may be easily torn from the tab. Although the tab may be of any desired shape, I preferably form it with a relatively narrow neck where it joins the body to inherently provide a line of weakness at this point.

In packaging the doilies within the container shown in Fig. 1, doilies of a single size or of assorted sizes are assembled in stacks with the tabs of all of the doilies registering with one another and they are introduced through the open top of the container and thereupon a wire staple 9 is passed through all of the tabs and through the backing, as shown best in Figs. 2 and 7. This staple serves to attach all of the doilies, in the positions shown, to the backing and between the backing 1 and the transparent display sheet and cover 4. When attaching the doilies to the back sheet as stated, I may position beneath the staple and overlying the tabs, a metal or plastic plate having an upstanding prong or hook 10, the purpose of which will be presently explained.

After the doilies have been assembled within the container and attached to the back sheet as described, the loose upper portion of the sheet 4 in Figs. 1 and 2 is folded upwardly and marginally secured along the lateral edges of the backing 1, while that portion which extends above the backing is bent downwardly over the edge of the backing and marginally adhesively secured to the rear face of the latter, so as to completely seal the doilies on all four sides within a closed container.

Fig. 3 shows such a closed container and illustrates the manner in which the doilies are commercially shipped. The arrangement of the doilies as shown makes it possible to see the different sizes and designs of the doilies within the container. In this condition, the packages

may be conveniently and efficiently displayed on sales counters and elsewhere in a manner to attract the ultimate consumer.

When such a package is bought and taken home, it may be stored until used in the condition specified. However, when one or more doilies are desired, the package is opened in the following manner:

While the main body portion of the package is held firmly in the hand or on a table with the finger piece extending over the edge, the finger piece 3 is grasped and bent back and forth about the axis of the line of weakness 2, until the finger piece breaks free from the remainder of the backing. In practice a relatively soft cardboard is used for the backing and the line of weakness is so constituted that the separation of the finger piece as stated may be readily accomplished.

After the finger piece 3 has been released from the remainder of the backing, the package is held firmly while the finger piece is drawn in the direction of the upper edge of the package. This operation causes the adhesively secured margins to be stripped from the backing after the manner appearing in Fig. 4. The relatively soft grade of cardboard used for the backing permits this separation of the margins to be readily accomplished. It is continued until the transparent sheet 4 is separated along its entire lateral edges, as shown in Fig. 5, so as to uncover and expose all of the doilies. One may then select from any of the three stacks D, D1, D2, such doilies as desired for the particular use at hand and the selected doilies may be individually removed by simply tearing them from their individual tabs along their lines of weakness 8.

As doilies are generally made of relatively thin paper stock and tend to cling to one another, there is always the probability that one or more doilies than are actually required may be removed. If this is done, the surplus doilies, designated d in Figs. 6 and 7, may be hung on the hook 10, as shown in these figures, where they will remain until they are desired for some subsequent use. Also additional doilies may be hung on the hook if so desired to replenish those of a size which may have been exhausted from the stock.

In the meantime the package may be most conveniently stored by hanging it upon the inside of a cupboard door by the employment of thumb tacks 11, indicated in Figs. 5 and 6, or in any other suitable manner. When thus hung in vertical position on a door, the backing 1 will tightly hug the surface of the door, while the transparent display sheet 4 will hang sheer over and cover the several doilies. The finger piece 3 will act as a stiffener for the cover sheet 4 to preclude any tendency which it might have to curl and at the same time impart to the lower edge of that sheet sufficient weight to cause it to hang nicely. Ordinarily one tab 7 is sufficient, but if the doilies are quite wide or long, it may be desirable to have more than one tab arranged along their upper edges, so as to suspend them more satisfactorily from the backing as will be readily understood.

The present invention provides a highly efficient package for paper doilies and enables them to be stored in a manner in which they will remain clean and serviceable until the last doily has been used.

An important feature of the present invention resides in the fact that the package of this in-

vention does not materially add to the cost of packaging as heretofore carried out while possessing features and advantages wholly absent from prior practice.

The foregoing detailed description sets forth the invention in its preferred practical form and the invention is to be understood as fully commensurate with the appended claims.

Having thus fully described the invention, what I claim as new and desire to secure by Letters Patent is:

1. A package comprising: a backing sheet provided across one end thereof with a finger piece joined to the remainder of the backing by a disruptable line of weakness, a stack of doilies 15 forwardly of said backing and having individual attaching tabs permanently secured to the backing, and a cover sheet marginally permanently secured to both the finger piece and to the opposite end of the backing and separably secured along the lateral margins of the backing, whereby said cover sheet may be stripped from said latter margins of the backing when the finger piece is separated from the backing, to expose the doilies for individual removal, said backing sheet being heavier than said cover sheet.

2. A package according to claim 1, wherein the cover sheet is transparent.

3. A package according to claim 1, wherein the backing is cardboard and the cover sheet is transparent.

4. A package according to claim 1, wherein there is included a plurality of stacks of doilies of different sizes, the attaching tabs of all of which register with and overlie one another and are secured to the backing by the same attaching means.

5. A package according to claim 1, including a hook to support within the package doilies inadvertently detached from their tabs, said hook being retained in place by means which also secures said tabs to said backing.

6. A sealed doily containing package comprising: a backing sheet having in spaced relation

to one of its ends a transverse disruptable line of weakness to provide at that end of the sheet a removable finger piece, a plurality of doilies, an individual supporting tab integral with each doily and extending beyond the periphery thereof and joined thereto by a rendable line of weakness, said doilies being stacked against the front face of the backing sheet with their tabs in superimposed relation, and means for attaching all of said tabs 10 to one another and to the backing sheet while leaving the doilies free from direct attachment to said sheet to permit them to be individually removed from the stack, in combination with a cover sheet overlying the front face of the backing sheet and said stack of doilies thereon, said cover sheet being permanently secured at one end to the finger piece and at its opposite end to the backing sheet in spaced relation to the doilies, and the lateral margins of both the cover and backing sheets being separably secured to one another remote from the doilies to provide a closed sealed envelope for said doilies, whereby the envelope may be unsealed by tearing the finger piece from the remainder of the backing sheet 25 along the interposed line of weakness and stripping the lateral margins of the cover sheet from the backing sheet to uncover the doilies for individual removal while leaving the cover sheet attached to the backing sheet at the end of the 30 latter remote from the finger piece.
